UNITED STATES PATENT OFFICE.

WARREN M. BRINKERHOFF, OF AUBURN, NEW YORK.

RECEIPT, CHECK, DRAFT, AND SIMILAR BOOKS.

SPECIFICATION forming part of Letters Patent No. 296,122, dated April 1, 1884.

Application filed October 9, 1883. (Model.)

To all whom it may concern:

Be it known that I, WARREN M. BRINKERHOFF, a citizen of the United States, residing at Auburn, in the county of Cayuga and State of New York, have invented new and useful Improvements in Receipt, Check, Draft, and Similar Books, of which the following is a specification.

This invention relates to improvements in receipt, check, draft, and similar books, and has for its object to provide a novel arrangement of the lines where the leaf is to be separated from the stub. In ordinary receipt, check, and similar books the usual lines of perforations between the leaf and stub are all arranged directly over each other in the same vertical plane, or else each succeeding one in rear of the preceding one, and when a few leaves are removed the remainder will in most instances tear into the body of the leaf, instead of directly along the line of perforations, for the reason that the edges of the stubs from which leaves have been removed project in a body, with their edges in line vertically, or practically so, by overhanging the lower stubs, thus preventing the leaves from tearing accurately along their lines of perforations. This is very objectionable and annoying, as will be well understood by those using such books, and the objection is avoided by my invention, to which end it consists, essentially, in a series of superposed leaves bound together in book form, and having perforated or otherwise weakened lines of separation, the separating-line of each succeeding leaf being arranged in advance of or out of line with the preceding one, whereby all the lines of separation are in different planes vertically, and the lower ones in advance of the upper ones, thus permitting every leaf in the series to be torn off or removed accurately on its line of separation, with no liability of tearing or injuring the body of the leaf.

The invention also consists in a series of superposed stubs and leaves having perforated or weakened lines of separation arranged out of line with each other vertically, said leaf carrying stubs being bound together in book form in such manner that each leaf of the series can be torn or removed from its stub on the weak-

ened line of separation without danger of tearing or injuring the body of the leaf.

The invention is illustrated in the accompanying drawings, in which Figure 1 represents a complete receipt-book made in accordance with my invention; Fig. 2, a similar view, several of the leaves being removed; and Fig. 3, a vertical sectional view.

Referring to the drawings, the number 1 indicates the binding, 2 the leaves, and 3 the stubs. The leaves may bear blank receipts, as usual; or they may be in the form of blank checks, drafts, telegraph-blanks, bills of lading, or other blanks which are to be filled in and then removed from its stub, leaving the latter secured in the binding. This, however, constitutes no part of my invention, the essential feature whereof consists in the arrangement of the lines of perforations or their equivalent, whereby the leaves can all be removed with ease and convenience without danger of tearing into the body of the leaf, as hereinbefore alluded to. To accomplish this I arrange the perforated or otherwise weakened lines 4 of separation so that the line of each succeeding leaf, commencing with the first one, is in advance of or out of line with the preceding line of separation, in such manner, as clearly represented by the drawings, that all the lines of separation are in different planes vertically and the succeeding lines in advance of the preceding lines, with respect to the thickness of the book. By this means every leaf of the entire series can be successively removed on its line of separation at a slight distance 75 from the edge of the stub of the previously detached leaf, so that such edge of the preceding stub in no manner interferes with the separation or removal of the succeeding leaf, as is the case in ordinary receipt and other books, 80 where all the lines of separation are directly over each and in the same vertical plane, or each succeeding line is in the rear of the preceding one. In such ordinary arrangement of the separating-lines, when a few leaves or 85 sheets are detached, the remainder will, in nearly every instance, tear into the body of the leaf, for the reason that the edges of the stubs from which leaves have been removed project in a body, with their edges in line vertically, 90

tically, or partially so, thus preventing the other attached leaves from being separated accurately along the lines of perforations, but, on the contrary, causing the succeeding leaves 5 to tear into their body portion when removed. Another advantage arising from my arrangement of the lines of separation is that a paper cutter or rule can be laid on the stubs and employed as a guide for tearing off all the 10 leaves of the series; but such is not requisite, but may be desired by some persons.

The invention can be used in all the various styles of receipt, check, draft, and similar books, and can be applied to large check, draft, 15 and similar books, where the checks or drafts are to be separated not only at one end, but also along their connecting sides, as will be readily understood without further illustration.

20 The stubs securing the leaves in position may or may not have lines and blank spaces for keeping a record of the matter contained on the leaves removed, and the lines of separation may be so closely arranged that while 25 the objects of my invention are attained the size of the book need not be unduly increased.

Having thus described my invention, what I claim is—

1. A series of superposed leaves secured in substantially the form of a book and having 30 weakened lines of separation, the line of succeeding leaves being in advance of the line of preceding leaves, substantially as described.

2. A receipt, check, draft, or similar book having its sheets provided with weakened lines 35 of separation, the line of each succeeding sheet being in advance of the preceding one, substantially as described.

3. A series of superposed leaves connected with stubs in book form by weakened lines of 40 separation, each succeeding line being in advance of the preceding one, substantially as described.

In testimony whereof I have hereunto set my hand in the presence of two subscribing witnesses. 45

WARREN M. BRINKERHOFF.
